INVENTOR,
By his Attorneys Alfred Hosack
Louis Bagger & Co.

UNITED STATES PATENT OFFICE.

ALFRED HOSACK, OF SILVER LAKE, INDIANA.

BRIDLE.

SPECIFICATION forming part of Letters Patent No. 250,920, dated December 13, 1881.

Application filed May 16, 1881. (No model.)

To all whom it may concern:

Be it known that I, ALFRED HOSACK, of Silver Lake, in the county of Kosciusko and State of Indiana, have invented certain new and useful Improvements in Bridles; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a bridle provided with my improvement. Fig. 2 is a longitudinal section of the brow-band detached. Fig. 3 is a similar view, showing a modified construction of the brow-band; and Fig. 4 is a perspective detail view of one end of the blinder-stay, showing the device for attaching it to the blinder.

Similar letters of reference indicate corresponding parts in all the figures.

My invention relates to stays for bridle-blinders; and it consists in the improvements hereinafter fully described, and particularly pointed out in the claims.

In the annexed drawings, A A represent the cheek-straps of a headstall or bridle. B is the nose-band, and C is the brow-band. D is the crown-piece, to the middle of which is 30 buckled a leather strap or billet, E, to the lower end of which is riveted a socketed plate, F, into which is inserted the bent middle part, g, of the blinder-stay G, which is secured adjustably within said plate F by means of a clamping-screw, f.

The brow-band C has a central slot, e, which may be formed either by inserting wedge-shaped pieces of leather or other material, b b, between the inner and outer straps composing the band, as shown in Fig. 2, or by riveting a loop or keeper, C', of nickel-plated metal or other suitable material, to the middle part of the band, as shown in Fig. 3; or, again, where

the brow-band has an ornamental plated strip running its entire length, as shown in Figs. 1 45 and 2 at d, the loop may be formed by striking up or raising the middle part of the band. The billet E, to the lower end of which the stay G is attached in the manner described, is inserted through the slot or opening e in the brow-band, which, it will thus be seen, prevents lateral motion or displacement of the billet and stay.

The blinders H H are attached by their upper outer corners to the ends of the stay G by means of small plates or castings I, the shank i of each of which has a screw-threaded recess, into which is screwed the outer threaded end of the stay. The outer end of each of these end plates, I, has a slot or opening, k, through which is inserted a small leather loop, K, (see Fig. 4,) 60 which is attached to the blinder. This means of attachment of the blinders to the stay affords a limited play for the former, so that they will not chafe or worry the horse, and yet be held sufficiently rigid in place to prevent undue motion or flapping.

Having thus described my invention, I claim and desire to secure by Letters Patent of the United States—

1. The blinder-stay G, provided with the detachable end plates, I, having screw-threaded shanks i and slots or openings k, substantially as set forth.

2. In a headstall or bridle, the blinder-stay G, provided with the detachable end plates, I, 75 having screw-threaded shanks i and slots k, in combination with the blinders H, having flexible loops K, substantially as and for the purpose herein shown and described.

In testimony that I claim the foregoing as in 80 my own I have hereto affixed my signature in presence of two witnesses.

ALFRED HOSACK.

Witnesses:

JOSEPH L. KIPLINGER,
J. ALLEN BOWDLE.
